H. J. VETTER

BOOK HANGER

Filed Dec. 11, 1922

Inventor

H. J. Vetter

By Watson E. Coleman
Attorney

UNITED STATES PATENT OFFICE.

HENRY J. VETTER, OF NEW YORK, N. Y.

BOOK HANGER.

Application filed December 11, 1922. Serial No. 606,081.

To all whom it may concern:

Be it known that I, HENRY J. VETTER, a citizen of the United States, residing at New York city, in the county of New York and 5 State of New York, have invented certain new and useful Improvements in Book Hangers, of which the following is a specification, reference being had to the accompanying drawings.

10 This invention relates to certain improvements in book hangers and it is an object of the invention to provide a novel and improved device of this general character which may be effectively engaged with a 15 book or the like to permit the book to be conveniently supported as desired.

It is also an object of the invention to provide a novel and improved device of this 20 general character embodying a pair of opposed penetrating members, said members being adapted to be forced within the book or the like in order to effect the requisite engagement of the hanger with the book.

The invention consists in the details of 25 construction and in the combination and arrangement of the several parts of my improved book hanger whereby certain important advantages are attained and the device rendered simpler, less expensive and other- 30 wise more convenient and advantageous for use, as will be hereinafter more fully set forth.

The novel features of my invention will 35 hereinafter be definitely claimed.

In order that my invention may be the 40 better understood, I will now proceed to describe the same with reference to the accompanying drawings, wherein:—

Figure 1 is a view in perspective illustrating a book hanger constructed in accordance with an embodiment of my invention; and

Figure 2 is a view in perspective illustrating a book hanger constructed in accordance 45 with a further embodiment of my invention.

In the form of invention illustrated in Figure 1, my improved hanger is formed of a single strand of wire of requisite gauge 50 and comprises the side member or bar 1 having its central portion coiled as at 2 whereby the opposite end portions of the bar 1 may be conveniently flexed yet at the same time urged in one direction upon the coils 2 being 55 placed under tension.

One extremity of the member or bar 1 is extended laterally to form an eye member 3 which is adapted to be engaged with a hook or other suitable support whereby my improved hanger can be employed with convenience and facility in suspending or hanging a book or the like with which the device is employed.

The eye member 3 is formed by looping a portion of the strand and then twisting the 65 same as at 4, said strand being then continued in a direction opposed to the eye member 3 to provide a side bar 5. The bar 5 terminates in an inwardly directed penetrating pin or member 6, said bar 5 intermediate its ends and at substantially its central portion is inwardly offset as at 7, and pivotally or hingedly connected with said offset portion 7 is a tie or holding bar 8.

The extremity of the bar 1 remote from 75 the eye member 3 is provided with a short arm 9 preferably formed by pinching the strand into substantially an eye member, the strand is continued from the arm 9 by the second side arm 10 normally substantially 80 in parallelism with the arm 5, said arm 10 also terminating in an inwardly directed penetrating pin or member 11. The arm 10 intermediate its ends and preferably at substantially its central portion is also provided 85 with an inwardly offset portion 12 with which is engaged a hook member 14 carried by the outer or free end portion of the holding or tie bar 8. The bars 1, 5 and 10 are substantially coplanar as also the penetrating pins or members 6 and 11.

When my improved hanger is applied to a book the outer or free end portions of the bars 5 and 10 are separated and which separating movement is facilitated by the 90 coils 2. The extent of separation is sufficient to permit the application of a book and particularly the corner portion of a book between the penetrating pins or members 6 and 11 whereupon said penetrating members 100 or pins 6 and 11 are caused to impinge the book and which can be readily effected by imposing relatively select pressure upon said members or pins 6 and 11. With my improved hanger thus engaged with a book, the book may be readily suspended as desired by engaging the eye member 3 with a suitably positioned support.

After the pins or members 6 and 11 have 105 been properly forced within the book or the 110

like the tie or holding bar 8 or particularly the hook 14 carried thereby is engaged with the inwardly offset portion 12 of the side bar 10 and whereby the arms 5 and 10 are effectively held against outward or separating movement and maintained in effective engagement with the book.

In the embodiment of my invention as illustrated in Figure 2 of the accompanying drawings, my improved hanger is constructed from a single sheet of material and comprises a substantially rectangular plate 15 provided at one end with a laterally and outwardly directed eye member 16 adapted to be engaged with a suitable support, said plate 15 at the same end is provided with an oppositely directed arm 17 with which is pivotally engaged as at 18 an extremity of a second arm 19, said arm 19 terminating in an inwardly directed penetrating pin or member 20.

The marginal portion of the plate 15 provided with the eye member 16 and at the opposite end of said plate is provided with an outstanding arm 21. The same end of the plate is provided with the oppositely directed elongated arm 22 extending in the same general direction as the arm 19 and also terminating in an inwardly directed penetrating pin or member 23. The swinging arm 19 readily permits the penetrating members 20 and 23 to be oppositely engaged with a book or the like and in order to maintain said pins in applied position I hingedly or pivotally connect as at 24 with the arm 19 a lock or tie bar 25, said bar 25 being provided with a hook member 26 adapted to engage the arm 22 and particularly a notch or recess 27 produced in the outer longitudinal marginal portion of said arm 22.

The arm 9 or the arm 21 is adapted to have engaged therewith an eye member 3 or 16 of a second hanger or the like so that said second hanger together with an as-

sociated hook or the like may be readily suspended from the first hanger. 45

In order to limit the extent of penetration of the pins or members 20 or 23 I find it of advantage to mount thereon the suitably positioned discs 28, said discs 28 also 50 operating to effect an effective clamping of the hook or the like between the arms 19 and 22, whereby the efficacy of the hanger is materially increased.

From the foregoing description it is 55 thought to be obvious that a book hanger constructed in accordance with my invention is particularly well adapted for use by reason of the convenience and facility with which it may be assembled and operated, 60 and it will also be obvious that my invention is susceptible of some change and modification without departing from the principles and spirit thereof and for this reason I do not wish to be understood as limiting myself 65 to the precise arrangement and formation of the several parts herein shown in carrying out my invention in practice except as hereinafter claimed.

I claim:—

A hanger for books comprising a body member provided with two relatively movable bars, said bars being provided with inwardly directed and opposed penetrating members, a holding bar carried by one of 75 the first named bars and provided with a hook member engageable with the second of the first named bars for holding the first named bars against separating movement, an eye member carried by one 80 end portion of the body member to provide a supporting means, the opposite end portion of the body member being provided with an outstanding arm.

In testimony whereof I hereunto affix my 85 signature.

HENRY J. VETTER.
